B. H. JENKS.
LOOM.

No. 12,630.

Patented Apr. 3, 1855.

UNITED STATES PATENT OFFICE.

BARTON H. JENKS, OF BRIDESBURG, PENNSYLVANIA.

LOOM.

Specification forming part of Letters Patent No. 12,630, dated April 3, 1855; Antedated January 8, 1855; Reissued June 5, 1855, No. 312.

To all whom it may concern:

Be it known that I, BARTON H. JENKS, of Bridesburg, in the county of Philadelphia and State of Pennsylvania, have invented 5 certain new and useful Improvements in Looms, of which the following is a full, clear, and exact description, reference being had to the accompanying drawings, which make part of this specification and in 10 which—

Figure 1 represents an isometrical view of a portion of the left end of the lay of the loom, and so much of the mechanism connected therewith as is necessary to show 15 the application of my improvements thereto; and Fig. 2 represents an elevation of the rear side of the same showing the shuttle boxes lifted a shelf higher than they appear in the view shown by Fig. 1.

20 In looms constructed as heretofore, the picker is very liable to be broken by the momentum with which the shuttle strikes it. With a view to remedy this defect and also to prevent the thread from being jarred off 25 the cop and entangled, I have arranged a spring lever a little beyond the outer end of the shuttle box for the picker to rest against, so that the momentum of the shuttle may be arrested gradually and thus 30 avoid the sudden blow or percussion with which the shuttle impinges upon the picker when held firmly and rigidly as in other looms.

The mechanism for relieving or freeing 35 the picker from the shuttle by a positive motion as heretofore patented by me, I have found to be although very useful, not quite as durable and certain in its action as in desirable, in consequence of the motion being 40 transmitted from the treadles to the shuttle through the intervention of a strap which is liable to stretch, so as to require frequent adjustment. To avoid this difficulty I have contrived an arrangement of 45 levers on the end of the lay, which in combination with a series of cams on the rod by which the shuttle boxes are lifted, so operates as to free the picker from the end of the shuttle preparatory to moving 50 the boxes.

In order to insure the prompt detachment of the picker from the end of the shuttle when the rest is withdrawn, I combine the picker by means of a string, link, or otherwise 55 with a spring lever, which constantly

tends to draw the picker toward the outer end of the lay.

In the accompanying drawing, a portion of the left end of the lay (A) is shown; also a piece of the sword (B) on which the end of the lay is supported; likewise a series of shifting shuttle boxes (C), and the lifting rod (D), by which the shuttle boxes are raised and depressed; also the picker (E) and the spindles or rods (F) on which it slides.

As mechanism for raising and lowering shuttle boxes, the picker stick, and other mechanism connected with the picking motion are well known, and fully described in 70 my former patents, I propose to omit all description of the same in the present application as superfluous except in so far as it may be necessary to refer to them in describing my present improvements.

75 On the front end of the lay (A), a bracket (G) is secured which extends downward; about the middle of this bracket the lower end of a lever (H) is secured by a pivot (a); and a spring I, extends from near the lower 80 end of the bracket, and the spring thus arranged constantly tends to turn the lever outward. The upper extremity of the lever is connected by a strap or cord (b) with the picker (E) so that the latter shall constantly 85 be pulled outward by the same force which tends to turn the upper end of the lever (H) in the same direction.

A bracket (J) is attached to the under 90 side of the lay, and extends downward. To the lower part of this bracket, an elbow or two arm lever (K) is held by a pivot (c) on which the lever turns. The upright and longest arm of the lever passes through a mortise or opening in the lay, and extends 95 up to a level with the top of the picker in order that the latter may rest against it, and thereby be limited in its outward motion. The horizontal arm of this lever (K) extends inward and rests upon the horizontal arm of a lever (L). The vertical arm (k) of the lever (K) is constantly drawn toward by a spring (M) which is connected to it, at one end, and at the other to the under side of the lay. Another 100 bracket (N) projecting downward from the under side of the lay supports the lever (P) which is connected with it by a pivot (n). The lower vertical arm of this lever, is provided with an obtuse wedge (d) projecting 105

from its inner edge. This wedge enters notches (*e*) of a corresponding shape on the side of a sleeve (Q) on the lifting rod (D).

The sleeve (Q) is attached to the lifting rod, and has a longitudinal rib on it, and as many obtuse angled notches in it as there are shuttle boxes, and at the same distance apart respectively, as the shelves of the same. Under this arrangement, whenever 5 the shuttle boxes are lifted by the rod (D) the movement of the sleeve up or down will force the wedge of the arm out of the notch in which it may be; at the commencement of this movement of the shuttle box, the 10 wedge will be forced out of the notch, and so held by the rib between the notches, until the box is changed to the required position to present another shuttle to the action of the picker, when the wedge will drop into 15 another notch, being forced therein by the pressure of the spring (M) acting through the lever (K) upon the lever (P).

When the wedge (*d*) is forced out of the notches the lower vertical arm (*p*) of the lever (P) is moved outward; this raises the horizontal arm (*P'*) and that in turn raises the horizontal arm (*k'*) of the lever (K) which moves the upper end of the arm (*k*) outward, thus permitting the spring lever (H) to draw the picker outward far enough to disengage it from the outer end of the shuttle as shown by red lines in Fig. 2.

The lever or rest is so arranged as to receive the blow of the picker, and yield without disturbing the position or action of the other lever (P) which transmits motion from the notched rib to effect the separation of the picker from the shuttle at the proper 35 time.

It will be observed that the tendency of the spring lever (H) is constantly to force the picker against its rest, while the tendency of the latter is to press against the picker, but the force with which the yielding rest presses inward must be so much greater than that which causes the picker to press outward, as to overcome it readily; otherwise the picker would not be returned after having been forced to its outermost 45 position by the momentum of the shuttle. 50

It is obvious that the spring bar can be worked from other parts of the box motion or can be worked by having a treadle in the loom. In that case the spring bar would be 55 moved backward by every revolution of the cam shaft.

What I claim as my invention, and desire to secure by Letters Patent, is—

1. The yielding rest or support for the 60 picker, arranged substantially as described, to break the sudden blow or concussion with which the shuttle impinges upon the picker, thereby preventing the filling of the cop 65 from being jarred off and entangled, and relieving the picker from danger of being broken.

2. I also claim separating or freeing the 70 picker from the end of the shuttle by the same movement which shifts the shuttle boxes, operating through a combination of levers, cams, and springs, substantially as herein set forth, or through levers, cams or treadles worked from any part of the room.

In testimony whereof, I have hereunto 75 subscribed my name.

BARTON H. JENKS.
